CLAIM

We claim the ornamental design for a wireless charger, as shown and described.

DESCRIPTION

FIG. 1 is a front perspective view of a wireless charger showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front view of the wireless charger, shown in a state of use with a pedestal feature.

The broken lines depict portions of the wireless charger that form no part of the claimed design. In FIG. 8, the broken lines showing a pedestal depict environmental subject matter only and form no part of the claimed design.

1 Claim, 5 Drawing Sheets
